(57) **CLAIM**

The ornamental design for a bottle, as shown and described.

DESCRIPTION

FIG. 1 shows a left perspective view of my design for a bottle;

FIG. 2 shows a right perspective view thereof;

FIG. 3 shows a bottom perspective view thereof;

FIG. 4 shows a top perspective view of a combination of several bottles according to the invention, interlocked with one another;

FIG. 5 shows a top perspective view of the configuration of FIG. 4;

FIG. 6 shows a bottom perspective view of the configuration of FIG. 4;

FIG. 7 shows a front view of the configuration of FIG. 4;

FIG. 8 shows a left and top perspective view of another combination of several bottles according to FIG. 1, in an interlocked position; and,

FIG. 9 shows a top plan view of the embodiment of FIG. 8. The areas shown in dotted lines are for environmental purposes only and form no part of the invention.
